2 Sheets-Sheet 2

UNITED STATES PATENT OFFICE.

WALTER D. CAMP, OF WETHERSFIELD, CONNECTICUT, ASSIGNOR TO ROYAL TYPEWRITER COMPANY, INC., OF NEW YORK, N. Y., A CORPORATION OF NEW YORK.

TYPEWRITING MACHINE.

Application filed May 13, 1922. Serial No. 560,707.

To all whom it may concern:

Be it known that I, WALTER D. CAMP, a citizen of the United States, residing at Wethersfield, in the county of Hartford and 5 State of Connecticut, have invented certain new and useful Improvements in Typewriting Machines, of which the following is a specification.

This invention relates to the paper supporting and guiding tables of typewriting machines in which a gage and an associated scale are provided at one end of the table to definitely position the edge of the paper relatively to the printing point on the 10 platen. Such gages and scales have heretofore been used in the Royal machines and are very serviceable in many classes of work.

According to my invention the table is formed near one end, preferably the left- 20 hand end, with a depression in which a graduated scale plate is adjustably mounted. A narrow elongated opening is made through the depressed portion of the table at each end of which there is a transverse 25 slot and ledges or flanges are formed above and below the narrow opening on which the scale plate rests, the opposite ends of the plate being passed through the slots at opposite ends of the opening and bearing against 30 the rear side of the table. A threaded stud, projecting rearwardly from the scale plate, extends through the elongated opening of the table and carries a clamping device by means of which the plate may be held in the 35 desired adjusted position.

The paper gage comprises a base portion 40 which extends across the table from top to bottom over the scale and which is provided on one side with a flange disposed at right angles to the body. An observation opening is formed in the base and also in the flange by means of which the scale may be inspected and a pointer, formed on the base portion of the gage, projects into the opening 45 over the scale.

The lower edge portion of the body of the gage is turned downward to form a lip which rests on the lower edge of the table, while the upper portion of the gage is extended over the top of the table and is prolonged to form an arm, which extends downwardly below the top of the table its lower portion being made to engage a horizontally arranged rod which extends across the machine in rear of the table.

In order to secure the gage to the supporting rod I employ a clamping device which engages the rod and which is attached to the arm of the gage by suitable devices. The clamp is formed with an arm or finger 60 which extends to the rear side of the table and bears against it in such manner as to hold the gage on its supporting rod yielding in order that it may not be moved accidentally but may be adjusted when desired. 65

The table has a smooth unbroken top over which the paper passes and it is carried by supporting arms which are attached to downwardly extending flanges of the table 70 so that no fastening devices appear on the top of the table. The upper and lower edge portions of the table are rolled or beaded as heretofore and a pad is provided on the machine frame on which the lower edge of 75 the table rests when in working position and against which it strikes when moved to such position.

The paper gage is so supported that it does not come in contact with the top of the table. It is held away from the table by the supporting arm before referred to which extends over the top of the table and by the lip at its lower edge portion which engages the table at its extreme lower end. Other 80 features of the invention will be hereinafter described. 85

In the accompanying drawings:—

Figure 1 is a side elevation of parts of a Royal typewriting machine with my improvements applied, some parts being shown in section for clearness of illustration and the raised position of the table being indicated by dotted lines. 90

Figure 2 is a view on an enlarged scale of some of the mechanism illustrated in Figure 1. 95

Figure 3 is a perspective view of the table and parts carried thereby detached from the carriage frame. 100

Figure 4 is a view on an enlarged scale and in section illustrating portions of the mechanism in rear of the table, the section being taken on the line 4—4 of Figure 2. 105

Figure 5 is a perspective view of the clamping device employed for connecting the gage with its supporting rod. 110

Figure 6 is a perspective view of a portion of the table illustrating clearly the depressed portion thereof and the elongated

opening and slots in the depressed part of the table.

Portions of the side plates of the carriage frame are indicated at A, and B indicates 5 a platen. C represents a type bar guide, D a margin stop rail and E a tabular rail. The top paper guide roll supporting arms F and the lower paper feed rolls G as shown 10 are of the usual Royal construction. The paper pan H extends under the platen and upwardly in rear thereof in the usual way and is supported at the rear by a frame piece I which carries a strip or pad J of felt or similar soft material which serves as a cushion 15 for the table when swung from its raised position to working position over the paper pan.

The paper table K is formed with upper 20 and lower curled or beaded edge portions k, k' and at its opposite sides with downwardly extending flanges k² to which the table supports or arms K' are secured. These table supporting arms are pivotally mounted 25 to move about the longitudinal axis of the tabular rail and they are equipped with springs e which serve to hold the table in either forward or rearward position as heretofore. When in operative position, the table is held against the pad J and should 30 it tend to vibrate, no noise is produced.

The table as thus constructed and mounted presents a smooth, attractive surface for supporting the paper and is free from the presence of the screws or securing devices 35 heretofore employed. It will be observed that the upper and lower portions of the table are smooth and unbroken and not cut away as heretofore.

The table is formed with a depression L 40 preferably at its left-hand end portion, although it may be thus formed at the right-hand end or at both ends if desired. This depression is of such size as to accommodate a scale plate M graduated to correspond with 45 the other letter space scales of the machine, being somewhat longer than the depressed portion of the table as indicated. This depressed part of the table is formed with a narrow elongated opening l which connects 50 at its opposite ends with slots l', l² which are somewhat longer than the width of the opening l and extend to the upper and lower edges of the depressed portion of the table. In this way, ledges l³ are produced which 55 serve to support the scale plate when it is inserted in the manner indicated in Figure 3, where it will be observed the opposite end portions of the scale are passed through the slots l', l² and bear against the rear face of 60 the table, while the middle portion of the plate rests on the ledges. The scale plate carries a threaded stud m which extends through the opening l and carries a washer m' and a clamping nut m². By these devices, the scale plate may be readily adjust- 65

ed to the desired extent and may be securely fastened in its adjusted position.

The paper gage N comprises a body portion n which extends transversely across the table from top to bottom thereof and is 70 formed with a flange n' disposed at right angles to the body. The gage extends across the scale and is formed in adjacent parts of the body and the flange with an observation opening x through which the scale may be 75 observed. The pointer N' formed integrally with the guide extends into the opening above the scale. The lower edge portion of the gage is formed with a lip or downwardly extending part n², which bears on the 80 lower beaded edge of the table as indicated most clearly in Figure 2. The upper part of the gage is bent over the top or upper edge of the table and is formed with an arm O which extends downwardly behind the table 85 and is formed with a concave lower portion o engaging a horizontally arranged rod P supported in the table arms K'.

In order to secure the gage to the supporting rod P I employ a clamp Q having a concave portion q fitting the rod P and an upper part q' having a central opening r to receive a short bolt R carrying a nut r'. The upper part of the clamp is formed with a lip r² which serves to prevent the nut from 90 turning on the bolt when the clamp is being applied and subsequently. The lower part of the clamp is formed with an arm or finger S which extends forwardly and bears 95 against the table yieldingly. By these devices the upper portion of the gage is held 100 away from or out of contact with the upper part of the table while the lower part of the gage is held away from the table by the lip n², the edge of which bears on the beaded lower portion of the table. It will thus be seen that the gage is held away from that portion of the table which supports the paper so that the gage may be moved freely 105 over the table which supports paper over 110 which the gage is moved, and a right hand additional gage may be used where split billing is being done; there is no danger of injury to the paper table. The upper part of the gage may be so supported on the rod P 115 that it may without loosening the clamping devices be moved crosswise of the machine to any desired extent and when once adjusted will be held frictionally in place without danger of being accidentally moved. It 120 will be observed that the spring finger or arm S has a yielding sliding connection with the table and the bolt R may be so adjusted as to permit the gage to be readily moved sidewise. If desired, the bolt may be 125 tightened to hold the gage securely in any position to which it may be adjusted.

By the devices shown, it is possible to adjust the gage definitely a given number of scale spaces corresponding with the letter 130

spaces on the machine, it being understood that the scale spacing of the scale plate M corresponds with the letter spaces on all other scales in the machine. The manner 5 in which the gage is used may be understood from a single illustration. If the pointer N' is located at zero and the margin stop on the machine is set at 20, it would indicate that there would be 20 spaces from the edge 10 of the sheet to be written upon to a point where printing would begin and if it be desired to add five more letter spaces or to diminish the margin to that extent it would be unnecessary for the operator to adjust 15 the margin stop, it being only necessary to adjust the paper gage five spaces to the right and the printing would begin at that point. If the operator has a set or predetermined margin which is always adhered to in the 20 usual width of paper, this relation can be assured and maintained at all times in case it is desired to move the gage to a position to the right to use paper narrower than the standard width and where a set margin is 25 still desired.

The table and scale is so designed as to facilitate the removal of the scale and the insertion of scales of different pitches. Instead of the factory having to make up a 30 large stock of paper tables of different pitch scales, the scale corresponding to the pitch of the machine may be inserted at the time of its being assembled in the machine. It will be observed that in the machine in 35 which my invention is employed, the margin stops and the tabular stops are located behind the table. Access thereto may be obtained by raising the table, but it is not always desirable to thus raise the table and 40 by utilizing the adjustable margin gage hereinbefore referred to suitable adjustments of the margin of the paper may be obtained without raising the table. The margin adjusting devices are in plain view 45 and within easy reach of the operator. This feature of the invention broadly considered is, however, shown, described and claimed in an application of Edward B. Hess and Lewis C. Myers, No. 473,162, filed May 27, 50 1921. The subject matter herein claimed as my invention is set forth in the accompanying claims.

I claim as my invention:—

1. A paper table for typewriting machines having an elongated opening extending lengthwise of it and having enlargements at its opposite ends to receive a scale plate. 55

2. A paper table for typewriting machines formed with an elongated opening and transverse slots at the opposite ends of the opening and formed also with ledges on opposite sides of the opening below the top surface 60 of the table for supporting a scale plate.

3. A paper table for typewriting machines 65 formed with an elongated opening and with slots at opposite ends of the opening, in combination with a scale plate of greater length than the opening and the opposite ends of which extend through the slots, and means 70 carried by the scale plate and extending through the table opening for securing the plate to the table.

4. A paper table for typewriting machines 75 formed with an elongated opening and with ledges above and below the opening below the surface of the table, and with slots at opposite ends of the ledges, in combination with a scale plate resting on the ledges and extending through said slots. 80

5. A paper table for typewriting machines provided near one end with a margin scale in combination with a paper gage movable on the table over the scale and formed with an opening through it and with a pointer 85 extending into the opening. 90

6. The combination with a paper table for typewriting machines carrying a margin scale, of a paper edge guide mounted on the table to move over the scale and having an angular flange formed with an opening through it above the scale joining an opening in the body of the gage, and a pointer 95 formed on the scale and projecting into said opening. 100

7. The combination with a paper table of a typewriting machine, of a paper guide extending across the table and out of contact therewith except at its lower edge, a rod located behind the table and engaged by a downwardly extending portion of the guide, and a clamping finger connected to the guide at one end, engaging the rod intermediate its ends, and resting against the back of the table at its other end whereby the guide may be moved along said rod but is held from rotation thereon. 105

8. The combination with a paper table of a typewriting machine, of a paper guide extending across the table and which has an arm bent over the top of the table without coming in contact therewith, a rod supported in rear of the table which is engaged by said arm, and a clamping device secured to the arm and engaging the rod and which has a yielding finger engaging the rear side of the table. 110

9. The combination with a table for typewriting machines, of a pad of relatively soft material mounted below the lower edge of the table, the arms pivotally mounted in the machine which support the table while its lower portion is in contact with said pad, said pad acting as a soft abutment for the table when it is swung into working position. 115 120 125

In testimony whereof, I have hereunto subscribed my name.

WALTER D. CAMP.
